Estelle Rentner, New York, N. Y.

Application September 14, 1940, Serial No. 95,028

Term of patent 3½ years

To all whom it may concern:

Be it known that I, Estelle Rentner, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design;

The characteristic feature of my design resides in the combination on the dress disclosed of the specific puffed trimming around the sleeves, neck and down the front thereof, each of the puffs of said trimming being separated by rhinestones as shown.

I claim:

The ornamental design for a dress, as shown and described.

ESTELLE RENTNER.
